TOILET PAPER HOLDER

George E. Noffsinger, Elkhart, Ind.

Application February 24, 1934, Serial No. 712,806

8 Claims. (Cl. 242—55.2)

My invention relates to toilet room fixtures, and particularly to devices for supporting a toilet paper roll.

The principal object of my invention is to provide a resilient non-metallic holder for toilet paper rolls.

Another object is to provide an improved toilet paper roll holder which comprises a pair of resilient soft rubber supporting arms provided with confronting trunnions adapted to carry the paper roll.

A third object of the invention is to provide an improved holder of the character described in which a pair of reinforced soft rubber paper roll supporting arms are incorporated.

Other and more specific objects of the invention are mentioned and described herein.

The invention is illustrated in the accompanying drawing, wherein

Figure 1 illustrates a top plan view of my improved toilet paper roll holder unit;

Figure 2 illustrates a side view of one of the holder arms;

Figure 3 illustrates a plan view of the holder arm broken away to disclose the reinforcing elbow therein, as suggested by the section line 3—3;

Figures 4 and 5 illustrate two views of the reinforcing elbow; and

Figure 6 illustrates a modified form of the holder invention.

Similar numerals of reference indicate like parts throughout the several views on the drawing.

Referring now to the details of the drawing the numerals 1 and 2 indicate a pair of cooperating opposed toilet paper supporting arms, preferably molded from soft rubber to impart resiliency thereto, each of said arms being provided with an integral laterally projecting bracket arm, as indicated by the numerals 3 and 4, respectively, said bracket arms being adapted to be fastened to a toilet room wall 5, or any other suitable element, as hereinafter described.

The soft rubber arms 1 and 2 are each provided with an integral soft rubber trunnion, as indicated by the numerals 6 and 7, respectively, which trunnions are in axial confronting relation when the said arms are mounted in operative position, said trunnions projecting from the outer end of said arms toward each other and are adapted to carry the tubular open end paper core 8 of a toilet paper roll 9. Preferably, the arm trunnions 6 and 7 are molded solid with the arm element and formed cylindrically to permit the roll core 8 to rotate thereon. And the trunnions 6 and 7 are

made of sufficient length to prevent casual dislodgment of the paper roll therefrom.

To impart semirrigidity to the bracket arms 3 and 4, which is very important in this holder unit, a reinforcing metal elbow 10, preferably made of flat or strip sheet metal, is molded or vulcanized within the arm unit, one leg of said elbow being molded within the bracket arm, and the other leg thereof being molded within the inner end of the arm, 1 or 2, whereby the major portion of the supporting arms 1 and 2 remain fully resilient. Each elbow leg which is molded within a bracket arm, 3 or 4, may be provided with a pair of screw holes 11 and 12 which register with suitable holes 13 in the rubber to admit the passage of fastener screws 14 to secure the arm members to the wall 5. Each of the elbows 10 may be provided also with holes 15 to enable the plastic rubber to fuse therethrough during the vulcanization thereof to maintain the juxtaposition of the elbow within the arm unit.

In the modification illustrated in Figure 6 the soft rubber arms 1 and 2 are integrally connected by a soft rubber body section 16, thereby providing a one piece soft rubber unit holder in which a sheet metal reinforcing member 17 is embedded, each end of said reinforcing member terminating in an elbow or arm 18 which extends into an arm 1 or 2 for a portion only of the length of the latter. In this modification the body 16 and member 17 are suitably apertured at 18 to admit the application of a fastener screw, or screws, therethrough.

It will be evident from the foregoing that the resiliency of the soft rubber arms 1 and 2 will enable the ready application of a paper roll to the confronting trunnions 6 and 7 as well as the easy and rapid removal of the roll core 8 therefrom after consumption of the paper from the roll.

It will be evident too that my improved soft rubber paper roll holder may be made in any desired color to match the color of a toilet room or the fixtures therein, thereby appealing to the æsthetic sense.

I claim:

1. A paper roll holder comprising a pair of resilient non-metallic supporting arms, each of said arms being provided with an integral laterally projecting paper roll trunnion adjacent the outer end thereof and an integral angular interiorly reinforced bracket arm at the opposite end thereof.

2. A paper roll holder comprising a pair of resilient non-metallic supporting arms, each of

said arms being provided with an integral laterally projecting paper roll trunnion adjacent the outer end thereof and an integral angular interiorly reinforced bracket arm at the opposite end thereof, said bracket arm and reinforcing means being apertured to receive fastener members.

3. In a paper roll holder a one piece resilient non-metallic supporting arm provided with an integral laterally projecting trunnion at the outer end thereof and an angular bracket arm at the other end thereof, and an L-shaped reinforcing element embedded in said supporting arm and the bracket arm thereof.

4. In a paper roll holder a one piece resilient soft rubber supporting arm provided with an integral laterally projecting trunnion at the outer end thereof and an angular bracket arm at the other end thereof, said bracket arm having a reinforcing element embedded therein.

5. A paper roll holder which comprises a one piece resilient soft rubber body and a pair of spaced supporting arms integral therewith and projecting angularly therefrom, said supporting arms being provided with integral confronting paper roll trunnions, and reinforcing means embedded in said body portion.

6. A paper roll holder comprising a pair of

resilient non-metallic supporting arms, each of said arms being provided with an integral laterally projecting paper roll trunnion adjacent the outer end thereof and an integral angular bracket arm at the opposite end thereof, and reinforcing means embedded in each of said arms and the bracket arm thereof.

7. A paper roll holder which comprises a one piece resilient soft rubber body and a pair of spaced supporting arms integral therewith and projecting angularly therefrom, said supporting arms being provided with integral confronting paper roll trunnions, and reinforcing means embedded in said body portion and extending into each supporting arm.

8. A paper roll holder comprising a pair of resilient non-metallic supporting arms, each of said arms being provided with an integral laterally projecting paper roll trunnion adjacent the outer end thereof and an integral angular bracket arm at the opposite end thereof, and reinforcing means embedded in each of said supporting arms and the bracket arm thereof, each bracket arm and its reinforcing means being provided with one or more registering apertures to receive fastener members.

GEORGE E. NOFFSINGER.
